William Goddard, Portsmouth, New Hampshire

Letters Patent.

The schedule referred to in these Letters Patent, and making part of the same, containing a description in the words of the said William Goddard himself of his improvements called the "New Portable Oven" for Roasting and Baking.

To all to whom these presents shall come.

Be it known that I William Goddard of Portsmouth, in the County of Rockingham and State of New Hampshire, have invented a new and useful improvement in the "Oven"; and that the following is a full and exact description of the construction and operation of the said improved oven as invented by me. First. Take a piece of thin American sheet iron or tin plates so riveted as to form a flat long square of sufficient size to form the outside of the oven except the bottom. The width of this plate being the length of the oven. This plate is then turned cylindrically until the shape of its ends is that of the greater segment of a circle (thus C). A flat sheet iron bottom of suitable thickness is then riveted on the edges of the plate so as to make the whole of the form of a cylinder with one side flat, which side is the bottom. A hole is then cut in the center of the bottom of the same diameter as that of the inner circumference of the furnace of the furnace to be used in heating the oven. A flat rim of wrought iron cast iron from two to three inches in width is riveted around this aperture to give it strength and durability. Two holes of from 16 to 18 inches in diameter, are cut with a punch in the upper part of the cylindrical side or top, one near each end, as apertures for chimneys and to equalize the heated air over the oven to be enclosed. A piece of sheet iron or tin plate similar in shape to the one first described and of suitable size, to form, when bent cylindrically, a lining to the cylinder before mentioned except the bottom, is inserted in such manner as to leave a space between said lining and the outside of oven to

101 inches, which space may be closed at the ends by bending the front and back edges of the lining and riveting them to the outer plate or by a rim of sheet iron of corresponding size. Two holes are then made in the upper surface of the lining opposite and corresponding to the holes in the outer surface, the lower edges of the lining being also riveted to the bottom. Through these holes in the top, flues or chimneys of sheet iron or tin are then inserted of sufficient length to create such a draught as is required for the combustion of the coal. These two chimneys are then connected by a horizontal funnel filled with a damper and of a length to conduct the heated air or gas to any required outlet. A head of sheet iron or tin, either single or lined, so as to leave a space between the two plates, is then fitted on and fastened to the end of the back of the oven. Near the top of this back a hole of sufficient size is cut with a punch to admit a tube for the escape of steam, when so required. The aforesaid spaces between the linings and outside covering may be filled with atmospheric air, wood ashes, powdered charcoal, or any other suitable nonconducting substance. A piece of sheet iron of a similar shape to the two before mentioned is then bent into the same cylindrical form and of such size as to leave when inserted into the other cylinder a space from $\frac{1}{2}$ to $\frac{3}{4}$ of an inch between the outside of this inner cylinder and the lining of the outer one. The inner cylinder having a bottom and similar and corresponding to the bottom and end of the outer cylinder, except that the bottom of the inner one is whole. A hole is then made near the top of the end of the said inner cylinder, corresponding in every respect to the hole in the outer one. The inner cylinder just described is perfectly the oven & the outer cylinder, together with its lining forms a nonconducting cover or case on the outside of the bottom of the oven is secured a plate of iron upright or end for the purpose of defending the bottom from the direct heat of the fire mass below. Supporters of iron are next fixed on the bottom of the inner cylinder or oven at suitable distances for the purpose

of keeping it in its proper position in the centre of the outer cylinder or case and preserving the space around for the passage of the heated air. A suitable rim of sheet iron or tin is then riveted on to the front end of the oven (whose edges are bent inwards & continued for the purpose) in order to close the space between the inner outer cylinders and to serve as a frame for the door, and is secured in such manner to the edge of the outer covering as to allow the oven to be withdrawn without much expense or trouble when repairs become necessary. A tube is next inserted through the apertures at the back of the oven fitted with a suitable stopper so that the tube may be open or closed at pleasure. The door may also be double & made of sheet iron or tin of sheet iron lined with tin. The usual apparatus inside, including a false bottom of sheet iron, handles at the top, and legs either fixed or movable by means of a thumb-screw so as to adapt the height of the bottom to the height of the furnace, complete the oven whole. The above described oven may be made of any other form or size upon the same principle.
